(57) CLAIM

The ornamental design for a mattress dimensions guide, as shown and as described.

DESCRIPTION

FIG. 1 is a first embodiment of a top view of a mattress dimensions guide showing my new design;

FIG. 2 is a bottom view thereof;

FIG. 3 is a left side view thereof, which is a mirror image of the right side view;

FIG. 4 is a front view thereof, which is a mirror image of the back view;

FIG. 5 is a second embodiment of a top view of the mattress dimensions guide; and,

FIG. 6 is a view of the mattress dimensions guide positioned in an apartment or home or other type of building.

The broken lines included in the figures of the mattress dimensions guide represent environmental structure and form no part of the claimed design.
